ROLLER GUIDE MEANS

Wilhelm Stahlecker, Tubingen, Germany, assignor to Vereinigte Kugellagerfabriken Aktiengesellschaft, Schweinfurt, Germany

Application November 13, 1950, Serial No. 195,192

17 Claims. (Cl. 19—130)

1

My present invention relates to a guide arm for the upper rollers of a textile fiber drawing mechanism.

One of the objects of my present invention is to provide a guide arm for the upper rollers of the drawing mechanism which will automatically align the axis of the upper rollers with those of the lower rollers.

An additional object of my present invention is to provide a guide arm which will automatically compensate for the inevitable inaccuracies in the construction of the guide arm.

A further object of my present invention is to provide a guide arm which may be easily removed from the rollers associated therewith.

A still further object of my present invention is to provide a guide arm which will have only a limited play so as to maintain the alignment of the upper rollers with the lower rollers.

With the above objects in view, my present invention mainly consists of a device for guiding the upper rollers of a textile fiber drawing mechanism in which the upper rollers are arranged in pairs, comprising, in combination, a guide arm having at least a first section and a second section arranged substantially along a straight line with an end portion of the first section located adjacent to a side portion of the second section, joint means for articulatively connecting the end portion of the first section with the side portion of the second section, means for connecting the guide arm to the upper rollers so that the upper rollers are free to rotate with respect to the guide arm, the first section having two separate side arms spaced from and arranged in parallel relation to each other, a cross member connecting the ends of the side arms which are distant from the connected end of the first section and a fulcrum element mounted on the drawing mechanism and located in abutting engagement with a central portion of the cross member, whereby the cross member and the side arms connected thereto cooperate with the fulcrum element in the manner of a pendulum so as to automatically compensate for differences in the lengths of the side arms.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

2

Fig. 1 is an elevational view, partly in section, of a guide arm according to a present day known construction;

Fig. 1a is a partial elevational view of the structure shown in Fig. 1 with the left hand rollers of Fig. 1 in a different position from that shown in Fig. 1;

Fig. 2 is a plan view, partly in section, of the structure shown in Fig. 1;

Fig. 3 is an elevational view, partly in section, of a guide arm constructed in accordance with my present invention;

Fig. 4 is a plan view, partly in section, of the structure shown in Fig. 3;

Fig. 5 is an end elevational view of the structure shown in Fig. 3 as viewed from the right hand end thereof;

Fig. 6 is an elevational view, partly in section, of another embodiment of a guide arm constructed in accordance with my present invention;

Fig. 7 is a plan view, partly in section, of the structure shown in Fig. 6;

Fig. 8 is an elevational view taken along line E—F of Fig. 6, and looking in the direction of the arrows;

Fig. 9 is an elevational view, partly in section, of a still further embodiment of a guide arm constructed in accordance with my present invention;

Fig. 10 is a sectional view taken along line G—H of Fig. 9 and looking in the direction of the arrows; and

Fig. 11 is a plan view of structure shown at the right hand end of Fig. 9.

Guide arms of the type to which my present invention relates are shown in U. S. Patent No. 2,246,474. Such a guide arm is illustrated in Figs. 1, 1a, and 2 and represents a known construction of guide arms.

In the known construction shown in Figs. 1 and 2, the upper rollers shown in the left portion of Fig. 1 are saddle loaded, whereas the upper roller in the right portion of Fig. 1 is loaded by its own weight. A plurality of the system shown in Figs. 1 and 2 are arranged in side by side relation and are generally located in a slightly inclined position with the right hand end of the system shown in Fig. 1 being slightly higher than the left hand end shown in Fig. 1. The lower rollers of the systems of the type shown in Fig. 1 which are arranged in side by side relation have their shafts connected to a source of rotative power so that these lower rollers are driven by the source of power and in turn drive the upper rollers in con-

tact therewith. Mounted on a through rod 15 are the guide arm support members 6 which are adjustably connected to the through rod 15 by means of the bolt 17 which clamps together the spaced portions of the supporting member shown at the right hand end of Fig. 1. Mounted in the recess 18 in element 6 is the pin 4 to which is connected the guide arm section 2.

It will be noted that this guide arm section 2 is formed of a single piece of metal which is bent centrally thereof to form two separate side arm portions on this section of the guide arm, the free ends of these side arms being bent so as to form the bearing joint portions 3a and 3b.

Section 1 of the guide arm shown in Figs. 1 and 2 is connected to the saddle members 19 and 20 by means of the bolts 21 and 22, respectively. Saddle member 20 has a pair of recesses which receive the end portions 3a and 3b therein so that section 1 of the guide arm is thereby connected to section 2 of the guide arm. Fixedly connected to saddle 19 is the hook 23 to which a weight is connected for loading the upper rollers shown at the left hand side of Fig. 1. Element 24 is a guide member for a clearer roller to be mounted above the upper roller 8.

It is evident that, in a guide arm of the type shown in Figs. 1 and 2 where guide arm section 2 is manufactured from one piece of metal, it is hardly possible to accurately construct the guide arm section 2 so that both of the bearing elements 3a and 3b are equally distant from the pivot 4 and symmetrically located with respect to a vertical plane passing perpendicularly through the lower rollers and through the pivot point 4. Only when these requirements are fulfilled, and also in certain exceptional cases, can the guide arm section 2 be accurately aligned with guide arm section 1 and the guide arm section 1 be in bearing engagement with both portions 3a and 3b.

Because the upper and lower rollers are not truly circular and because windings form on the rollers, the guide arm section 1 will necessarily make linear and lateral movements which must be limited, for various reasons, by the guide arm section 2. Because of the unsymmetrical position of the bearing joints 3a and 3b, there is a tendency for a lateral movement of the section 1 which is much greater than its limits permit. The result is that guide arm section 1 rubs against guide arm section 2 and the position of the upper rollers in parallel relation to the lower rollers does not obtain.

A further result is that only one of the bearing elements 3a and 3b is in engagement with guide arm section 1 so that a lateral turning of guide arm section 2 occurs which causes the central portion of the upper rollers 7a and 8 to be moved out of the vertical plane passing perpendicularly through the lower rollers and through the pivot 4.

My present invention overcomes these defects principally by means of a two section guide arm. The sections of the guide arm are connected together in such a way that they are free to move with respect to each other and so that the unavoidable differences in the dimensions of the sides of the guide arm section 2 are automatically compensated for.

One embodiment of my present invention for overcoming the above mentioned defects in known guide arms, is shown in Figs. 3 and 5 where the member corresponding to guide arm section 2 of Figs. 1 and 2 is no longer made of a single piece of metal. As is shown in Fig. 4, two separate arms 2a and 2b are connected at their

ends to a cross member 2c. The cross member 2c has reduced end portions which pass through apertures formed in the ends of the elements of 2a and 2b, respectively, so that the arms 2a and 2b are freely mounted with respect to cross member 2c. The connection of elements 2a and 2b to guide arm section 1a by means of the bearing joint portions 3c and 3d, respectively, is the same as that described in connection with Figs. 1 and 2.

In the form of my present invention which is illustrated in Figs. 3 to 5, the guide arm support 6a comprises a pair of longitudinal side portions 26 and 27 and a pair of grooves 28 and 29 formed at the lower inner sections of these side portions. Between the side portions 26 and 27 is mounted a block 32 having a pair of projections 30 and 31 located in the grooves 28 and 29, respectively. The block 32 has a portion thereof cut away so as to permit cross member 2c to extend across the block 32. Threadedly mounted through a substantially vertical threaded opening in block member 32 is the fulcrum element 4a against which cross member 2c bears. The position of the upper rollers may be adjusted by moving block 32 along support member 6a, and block 32 may be fixed in any desired position by turning screw 4a so that the projections 30 and 31 bear against the upper surfaces of grooves 28 and 29, respectively. Roving guide member 33 is shown in Fig. 3.

It will be noted that, due to the arrangement of guide arm section 2a, 2b, 2c shown in Figs. 3 to 5, the arms 2a and 2b and the cross member 2c connected thereto may move about fulcrum element 4a in the nature of a pendulum so that bearing portions 3c and 3d are always in contact with guide arm section 1a. If arm 2a, for example, is moved in one direction, arm 2b necessarily moves in the opposite direction, and in this manner any differences in the dimensions of the arms 2a and 2b are automatically compensated.

The guide arm sections 1a and 2a, 2b, 2c are therefore constantly in alignment with each other, and all of the necessary movements of the entire guide arm are freely permitted. In order to guarantee a quick automatic parallel alignment of the axes of the upper rollers with those of the lower rollers, the lateral movements of guide arm section 1a with respect to guide arm section 2a, 2b, 2c are narrowly limited, as well as the lateral movements of guide arm section 2a, 2b, 2c. The lateral movement of guide arm section 1a with respect to guide arm section 2a, 2b, 2c is limited by the location of guide arm section 1a between elements 2a and 2b, as shown in Fig. 4, and by the minimum of side play permitted between the bearing portions 3c and 3d and the recesses in the saddle element 20a shown in Fig. 4. The lateral movement of elements 2a and 2b is limited by the small clearance which is provided between these elements and the inner surface of side portions 26 and 27 of the support member 16. A narrow limiting of these lateral movements permits the entire guide arm and the upper rollers connected thereto to be conveniently and effectively controlled.

Figs. 6 to 8 show another embodiment of a construction for carrying out my present invention. In this embodiment the guide arm section is formed of two separate arms 2f and 2g. However, at the left hand end of these arms, as viewed in Figs. 6 and 7, the bearing portions have been replaced by hook-shaped end portions 2d formed integrally with side arms 2f and 2g. Instead of a cross member similar to 2c, shown

in Figs. 3 and 4, the connecting cross member 2e shown in Fig. 7 comprises an aperture extending therethrough perpendicularly to arms 2f and 2g and having an annular projection 34 located therein.

Through the aperture in element 2e and in engagement with projection 34 is located the fulcrum member 35 which is supported within slots 36 passing through the side portions 26a and 27a of support 6b. This fulcrum member 35 may be adjustably connected by means of a thread thereon and the nut 37 at any position along the slots 36 so as to thereby adjust the positions of the top feed rollers and top middle rollers.

It will be noted that the hook-shaped end portions 2d engage the shaft 7 of upper roller 7a so that there is provided between guide arm sections an extremely strong, simple and rigid connection wherein the shaft 7 itself forms a pivot between the sections. Due to this type of connection it is only necessary to raise guide arm section 1e and roller 8 in order to correct any trouble which may have occurred during the operation of the machine, and the roller 7a will remain in the position shown in Fig. 6. It will not move from this position as it does with the form of guide arm shown in Figs. 1 and 2. This movement of roller 7a is illustrated in Fig. 1a and is particularly harmful in a double apron drawing system.

In order to eliminate, as much as possible, play between guide arm sections, there is provided a pin 38 on which is mounted the spring 10 which presses the arms 2a and 2b outwardly against the inner surfaces of the depending portions of saddle member 20b, as is clearly shown in Figs. 7 and 8.

One advantage of the construction shown in Figs. 6 to 8 is that the guide arm section 2f, 2g may be turned up to the dotted line position illustrated in Fig. 6, after guide arm section 2f, 2g has been disconnected from shaft 7, so as to give access to the rollers located beneath guide arm section 2f, 2g.

The construction shown in Figs. 6 to 8 permits guide arm section 1c to be separated from guide arm section 2f, 2g simply by moving the shaft 7 out of the hook-shaped portions 2d, so that guide arm section 2f, 2g may then be turned up to the dotted line position shown in Fig. 6. Guide arm section 2f, 2g or its support member 6b may be constructed in any known manner so that the guide arm section 2f, 2g will remain in the dotted line position shown in Fig. 6. In contrast to this, the guide arm sections 1 and 2 shown in Figs. 1 and 2 cannot be easily separated from each other and can only be moved up to a limited degree, as is evident from Fig. 1a.

While the spring 10 eliminates undesirable play between the guide arm sections, the force of the spring is small enough to provide only a slight friction between saddle member 20b and ends 2d of guide arm section 2f, 2g, so that guide arm section 1c may be easily turned with respect to guide arm section 2f, 2g. The construction shown in Figs. 6 to 8 therefor provides the desired alignment of the guide arm section, as described above.

In addition to the lateral movement of arms 2f and 2g, in Figs. 6 and 7, being limited by side portions 26a and 27a, as described above, this lateral movement is further limited to the space between the pin 35 and the aperture extending through cross member 2e.

Figs. 9 to 11 show a further embodiment of my present invention in which the three upper rollers

are all saddle loaded. In this form of the invention, the rear guide arm section again includes the arms 2h and 2i similar to those shown in Figs. 6 and 7 and which are also pressed by spring 10a against the inner surfaces of depending portions of the saddle member 39 which is constructed differently from saddle member 20b. Connecting the right hand end portions of arms 2h and 2i, as viewed in Figs. 9 and 11, is the cross member 2j having the annular projection 40 thereon. The fulcrum member of this embodiment comprises an extension 41 of support member 6' which has a substantial planar surface located adjacent to cross member 2j and in abutting engagement with annular projection 40.

The pendulum-like movement of guide arm section 2h, 2i, shown in Figs. 9 and 11, is limited by contact between the outer surface of cross member 2j with the adjacent surface of fulcrum element 41. It is evident that the guide arm section shown in Figs. 9 and 11 possesses all of the dimension compensating and self-alignment features which are possessed by the guide arm sections described above in connection with the embodiments of the invention shown in Figs. 3 and 6, respectively.

Saddle member 39 itself forms a part of the forward guide arm section and is connected to arm 1b in any suitable manner, e. g. by a structure shown in dotted lines in Fig. 9 consisting of a bifurcated element 50 and a cross member 51. The bifurcated element is formed with an opening passing transversely therethrough and the elongated arm 1b extends through this opening. A threaded opening extends through a portion of the bifurcated element which overlies the arm 1b, and a set screw 52 is threadedly mounted in this last mentioned opening, so as to rigidly connect the bifurcated element to the arm 1b. The bifurcations of the bifurcated element 50 are mounted on opposite sides of the cross member 51 which extends across the space between the depending side portions of saddle member 39. In order to have the bifurcated element 50 fit loosely between the sides of the saddle member 39 clearances are provided on both sides between the saddle member and said element.

By means of this aforementioned structure the arm 1b may be fixed in position with respect to the saddle member 39 by tightening the set screw, while upon loosening the set screw the arm 1b can easily be adjusted or removed. Member 39 is formed with an opening (not shown) over the screw 52 so that the latter is easily reached.

The rod 42 for supporting the weight which loads the upper rollers of Fig. 9 is seated in a notch provided in the upper part of arm 1b, there being a number of notches provided for adjustment of rod 42. The notches are not shown in the figure.

Clockwise rotation of element 39 about shaft 7 is limited by means of extensions 12 which are formed integrally with the depending portions of saddle 39 and which engage stop member 11 formed on arms 2h and 2i. When the load has been removed from element 42 and when arm 1b has been disconnected from member 39, this member 39 may be turned up to the dotted line position shown in Fig. 9 to give access to the lower rollers.

It will be understood that each of the elements described above, or two or more together, may also find a useful application in other types of roller guide means differing from the types described above.

While I have illustrated and described the invention as embodied in guide means for upper rollers in a textile drawing machine, I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What I claim as new and desire to secure by Letters Patent is:

1. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other; a cross member connecting the ends of said side arms which are distant from said connected end of said first section; and a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms.

2. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane passing perpendicularly through the lower rollers of the drawing mechanism; a cross member connecting the ends of said side arms which are distant from said connected end of said first section; and a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms.

3. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane passing perpendicularly through the lower rollers of the drawing mechanism; a cross member connecting the ends of said side arms which are distant from said connected end of said first section; a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms; and means for limiting the movement of said cross member and said side arms connected thereto about said fulcrum element.

4. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane passing perpendicularly through the lower rollers of the drawing mechanism; a cross member pivotally connected to the ends of said side arms which are distant from said connected end of said first section so that said side arms may pivot in a vertical plane with respect to said cross member; a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms; and means for limiting the movement of said cross member and said side arms connected thereto about said fulcrum element.

5. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of

said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane passing perpendicularly through the lower rollers of the drawing mechanism and said second section also being arranged in substantially parallel relation to a vertical plane passing perpendicularly through the lower rollers of the drawing mechanism; a cross member pivotally connected to the ends of said side arms which are distant from said connected end of said first section so that said side arms may pivot in a vertical plane with respect to said cross member; a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms; and means for limiting the movement of said cross member and said side arms connected thereto about said fulcrum element.

6. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane passing perpendicularly through the lower rollers of the drawing mechanism and said second section also being arranged in substantially parallel relation to a vertical plane passing perpendicularly through the lower rollers of the drawing mechanism; a cross member pivotally connected to the ends of said side arms which are distant from said connected end of said first section so that said side arms may pivot in a vertical plane with respect to said cross member; a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms; and means for limiting the movement of said cross member and said side arms connected thereto about said fulcrum element, said joint means for articulatively connecting said guide arm sections to each other comprising a pair of end portions located respectively on said side arms and each forming a substantially right angle bend with the remainder of said side arms, and a pair of recesses formed in said side portion of said second section and in which said end portions of said side arms are received.

7. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane passing perpendicularly through the lower rollers of the drawing mechanism and said second section also being arranged in substantially parallel relation to a vertical plane passing perpendicularly through the lower rollers of the drawing mechanism; a cross member pivotally connected to the ends of said side arms which are distant from said connected end of said first section so that said side arms may pivot in a vertical plane with respect to said cross member; a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms; means for limiting the movement of said cross member and said side arms connected thereto about said fulcrum element; and a shaft on which the upper rollers nearest to said joint means are rotatably mounted, said joint means comprising a pair of hook-shaped end portions formed respectively at the ends of said side arms adjacent said side portion of said second section, the said hooked-shaped end portions embracing said shaft.

8. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane passing perpendicularly through the lower rollers of the drawing mechanism and said second section also being arranged in substantially parallel relation to a vertical plane passing perpendicularly through the lower rollers of the drawing mechanism; a cross member pivotally connected to the ends of said side arms which are distant from said connected end of said first section so that said side arms may pivot in a vertical plane with respect to said cross member; a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms; and means for limiting the movement of said cross member and said side arms connected thereto about said fulcrum element, said joint means for articulatively connecting said guide arm sections to each other comprising a pair of end portions located respectively on said side arms and each forming a substantially right angle bend with the remainder of said side arms, and a pair of recesses formed in said side portion of said second section and in which said end portions of said side arms are received.

side arms connected thereto cooperate with said fulcrum element in the manner of a pendulum so as to automatically compensate for differences in the lengths of said side arms; and means for limiting the movement of said cross member and said side arms connected thereto about said fulcrum element comprising a supporting member on which said fulcrum element is located and a pair of longitudinal side portions mounted on said supporting member and located adjacent to but slightly spaced from said side arms so as to provide a slight space for play of said side arms before they contact said side portions.

9. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane passing perpendicularly through the lower rollers of the drawing mechanism and said second section also being arranged in substantially parallel relation to a vertical plane passing perpendicularly through the lower rollers of the drawing mechanism; a cross member pivotally connected to the ends of said side arms which are distant from said connected end of said first section so that said side arms may pivot in a vertical plane with respect to said cross member; a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms; means for limiting the movement of said cross member and said side arms connected thereto about said fulcrum element; and a shaft on which the upper rollers nearest to said joint means are rotatably mounted, said joint means comprising a pair of hook-shaped end portions formed respectively at the ends of said side arms adjacent said side portion of said second section, the said hook-shaped end portions embracing said shaft, said means for connecting said guide arm to said upper rollers comprising a hollow saddle member mounted on said second section of said guide arm and having depending portions which embrace said shaft, said hook-shaped end portions of said side arms being located within said depending portions of said saddle member; and means for limiting the movement of said first section with respect to said second section comprising a spring mounted between said side arms so as to push the hook-shaped end portions thereof against said depending portions of said saddle member.

10. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane

11. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane passing perpendicularly through the lower rollers of the drawing mechanism and said second section also being arranged in substantially parallel relation to a vertical plane passing perpendicularly through the lower rollers of the drawing mechanism; a cross member pivotally connected to the ends of said side arms which are distant from said connected end of said first section so that said side arms may pivot in a vertical plane with respect to said cross member; a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms; means for limiting the movement of said cross member and said side arms connected thereto about said fulcrum element; and a shaft on which the upper rollers nearest to said joint means are rotatably mounted, said joint means comprising a pair of hook-shaped end portions formed respectively at the ends of said side arms adjacent said side portion of said second section, the said hook-shaped end portions embracing said shaft, said means for connecting said guide arm to said upper rollers comprising a hollow saddle member mounted on said second section of said guide arm and having depending portions which embrace said shaft, said hook-shaped end portions of said side arms being located within said depending portions of said saddle member; and means for limiting the movement of said first section with respect to said second section comprising a spring mounted between said side arms so as to push the hook-shaped end portions thereof against said depending portions of said saddle member.

12. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane passing perpendicularly through the lower rollers of the drawing mechanism and said second section also being arranged in substantially parallel relation to a vertical plane passing perpendicularly through the lower rollers of the drawing mechanism; a cross member pivotally connected to the ends of said side arms which are distant from said connected end of said first section so that said side arms may pivot in a vertical plane with respect to said cross member; a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms; means for limiting the movement of said cross member and said side arms connected thereto about said fulcrum element; and a shaft on which the upper rollers nearest to said joint means are rotatably mounted, said joint means comprising a pair of hook-shaped end portions formed respectively at the ends of said side arms adjacent said side portion of said second section, the said hook-shaped end portions embracing said shaft, said means for connecting said guide arm to said upper rollers comprising a hollow saddle member mounted on said second section of said guide arm and having depending portions which embrace said shaft, said hook-shaped end portions of said side arms being located within said depending portions of said saddle member; and means for limiting the movement of said first section with respect to said second section comprising a spring mounted between said side arms so as to push the hook-shaped end portions thereof against said depending portions of said saddle member.

located in abutting engagement with a central portion of said cross member, whereby said cross member and said side arms connected thereto cooperate with said fulcrum element in the manner of a pendulum so as to automatically compensate for differences in the lengths of said side arms; and a shaft on which the upper rollers nearest to said joint means are rotatably mounted, said joint means comprising a pair of hook-shaped end portions formed respectively at the ends of said side arms adjacent said side portion of said second section, the said hook-shaped end portions embracing said shaft, said means for connecting said guide arm to said upper rollers comprising a hollow saddle member mounted on said second section of said guide arm and having depending portions which embrace said shaft, said hook-shaped end portions of said side arms being located within said depending portions of said saddle member; and means for limiting the movement of said first section with respect to said second section comprising a spring mounted between said side arms so as to push the hook-shaped end portions thereof against said depending portions of said saddle member, said cross member being formed with an aperture extending therethrough in a direction which is substantially perpendicular to said side arms, said fulcrum element comprising a fixedly mounted pin extending through said aperture, and a projection mounted on said cross member and bearing against the outer surface of said pin and said pin being of a substantially smaller cross-section than said aperture so that a space is provided between the outer surface of said pin and the surface of said aperture, whereby the movement of said cross member and said side arms connected thereto about said pin is limited to said space between said pin and said aperture.

12. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane passing perpendicularly through the lower rollers of the drawing mechanism and said second section also being arranged in substantially parallel relation to a vertical plane passing perpendicularly through the lower rollers of the drawing mechanism; a cross member pivotally connected to the ends of said side arms which are distant from said connected end of said first section so that said side arms may pivot in a vertical plane with respect to said cross member; a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms; and a shaft on which the upper rollers nearest to said joint means are rotatably mounted, said joint means comprising a pair of hook-shaped end portions formed respectively at the ends of said side arms adjacent said side portion of said second section, the said hook-shaped end por-

ed, said joint means comprising a pair of hook-shaped end portions formed respectively at the ends of said side arms adjacent said side portion of said second section, the said hook-shaped end portions embracing said shaft, said means for connecting said guide arm to said upper rollers comprising a hollow saddle member mounted on said section of said guide arm and having depending portions which embrace said shaft, 10 said hook-shaped end portions of said side arms being located within said depending portions of said saddle member; means for limiting the movement of said first section with respect to said second section comprising a spring mounted between said side arms so as to push the hook-shaped end portions thereof against said depending portions of said saddle member, said cross member being formed with an aperture extending therethrough in a direction which is substantially perpendicular to said side arms, said fulcrum element comprising a fixedly mounted pin extending through said aperture, and a projection mounted on said cross member and bearing against the outer surface of said pin and said pin being of a substantially smaller cross-section than said aperture so that a space is provided between the outer surface of said pin and the surface of said aperture, whereby the movement of said cross member and said side arms connected thereto about said pin is limited to said space between said pin and said aperture; a slot formed in said drawing mechanism in which said pin is received; and means for adjustably fixing said pin at any desired location in said slot whereby the position of said upper rollers may be regulated.

13. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane passing perpendicularly through the lower rollers of the drawing mechanism and said second section also being arranged in substantially parallel relation to a vertical plane passing perpendicularly through the lower rollers of the drawing mechanism; a cross member pivotally connected to the ends of said side arms which are distant from said connected end of said first section so that said side arms may pivot in a vertical plane with respect to said cross member; a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms; and a shaft on which the upper rollers nearest to said joint means are rotatably mounted, said joint means comprising a pair of hook-shaped end portions formed respectively at the ends of said side arms adjacent said side portion of said second section, the said hook-shaped end por-

tions embracing said shaft, said means for connecting said guide arm to said upper rollers comprising a hollow saddle member mounted on said second section of said guide arm and having depending portions which embrace said shaft, said hook-shaped end portions of said side arms being located within said depending portions of said saddle member; and means for limiting the movement of said first section with respect to said second section comprising a spring mounted between 10 said side arms so as to push the hook-shaped end portions thereof against said depending portions of said saddle member, said cross member being formed with an aperture extending therethrough in a direction which is substantially perpendicular to said side arms, said fulcrum element comprising a fixedly mounted pin extending through said aperture, and a projection mounted on said cross member and bearing against the outer surface of said pin and said pin being of a substantially smaller cross-section than said aperture so that a space is provided between the outer surface of said pin and the surface of said aperture, whereby the movement of said cross member and said side arms connected thereto about said pin is limited to said space between said pin and said aperture and whereby said side arms are free to rotate with said cross member about the axis of said pin so that, when said hook-shaped end portions of said side arms are disconnected from said upper roller shaft, said side arms may be turned up to give access to rollers located beneath said side arms.

14. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane passing perpendicularly through the lower rollers of the drawing mechanism and said second section also being arranged in substantially parallel relation to a vertical plane passing perpendicularly through the lower rollers of the drawing mechanism; a cross member pivotally connected to the ends of said side arms which are distant from said connected end of said first section so that said side arms may pivot in a vertical plane with respect to said cross member; a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms; and a shaft on which the upper rollers nearest to said joint means are rotatably mounted, said joint means comprising a pair of hook-shaped end portions formed respectively at the ends of said side arms adjacent said side portion of said second section, the said hook-shaped end portions embracing said shaft, said means for connecting

5 said guide arm to said upper rollers comprising a hollow saddle member mounted on said second section of said guide arm and having depending portions which embrace said shaft, said hook-shaped end portions of said side arms being located within said depending portions of said saddle member; and means for limiting the movement of said first section with respect to said second section comprising a spring mounted between 10 said side arms so as to push the hook-shaped end portions thereof against said depending portions of said saddle member, said cross member having an annular projection located centrally thereof, said fulcrum element having a substantially planar surface against which said annular projection bears and which is slightly spaced from the cross member, so that the movement of said cross member and said side arms connected thereto about said fulcrum element is limited by the contact of a portion of said cross member with said surface of said fulcrum element.

15. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other, each of said side arms being arranged in substantially parallel relation to a vertical plane passing perpendicularly through the lower rollers of the drawing mechanism and said second section also being arranged in substantially parallel relation to a vertical plane passing perpendicularly through the lower rollers of the drawing mechanism; a cross member pivotally connected to the ends of said side arms which are distant from said connected end of said first section so that said side arms may pivot in a vertical plane with respect to said cross member; a fulcrum element mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms; and a shaft on which the upper rollers nearest to said joint means are rotatably mounted, said joint means comprising a pair of hook-shaped end portions formed respectively at the ends of said side arms adjacent said side portion of said second section, the said hook-shaped end portions embracing said shaft, said means for connecting said guide arm to said upper rollers comprising a hollow saddle member mounted on said second section of said guide arm and having depending portions which embrace said shaft, said hook-shaped end portions of said side arms being located within said depending portions of said saddle member, said side arms each having a projection on the surface thereof and said saddle member having a pair of projections in engagement with said projections of said side arms so as to limit the rotation of said saddle mem-

ber about said shaft; and means for limiting the movement of said first section with respect to said second section comprising a spring mounted between said side arms so as to push the hook-shaped end portions thereof against said depending portions of said saddle member, said cross member having an annular projection located centrally thereof, said fulcrum element having a substantially planar surface against which said annular projection bears and which is slightly spaced from the cross member, so that the movement of said cross member and said side arms connected thereto about said fulcrum element is limited by the contact of a portion of said cross member with said surface of said fulcrum element.

16. A device for guiding the upper rollers of a textile fiber drawing mechanism in which the upper rollers are arranged in pairs, comprising, in combination, a guide arm having at least a first section and a second section arranged substantially along a straight line with an end portion of said first section located adjacent to a side portion of said second section; joint means for articulatively connecting said end portion of said first section with said side portion of said second section; means for connecting said guide arm to the upper rollers so that the upper rollers are free to rotate with respect to said guide arm; said first section having two separate side arms spaced from and arranged in parallel relation to each other; a cross member connecting the ends of said side arms which are distant from said connected end of said first section; and a fulcrum element comprising a pin which is supported in a substantially vertical position and which is mounted on said drawing mechanism and located in abutting engagement with a central portion of said cross member, whereby said cross member and said side arms connected thereto cooperate with said fulcrum element in the manner of a pendulum so as to automatically compensate for differences in the lengths of said side arms.

17. A device for guiding the upper rollers of a textile fiber drawing mechanism in which the upper rollers are arranged in pairs, comprising, in combination, a guide arm having at least a first section and a second section arranged substantially along a straight line with an end por-
